UNITED STATES PATENT OFFICE.

ALFRED E. ROBERTS, OF SAN FRANCISCO, CALIFORNIA.

CARBURETOR.

Application filed July 28, 1919. Serial No. 313,810.

To all whom it may concern:

Be it known that I, ALFRED E. ROBERTS, citizen of the United States, residing at San Francisco, in the county of San Francisco, 5 State of California, have invented a new and useful Carburetor, of which the following is a specification in such full and clear terms as will enable those skilled in the art to construct and use the same.

This machine is for the purpose of producing a mixture of fuel and air for heating or lighting purposes where the usual coal or oil gas is not available.

The main objects of my invention are to 15 provide a machine which will at all times produce a fuel mixture of the proper richness and with means for so controlling the temperature of the incoming air and evaporating liquid fuel that danger of freezing 20 is eliminated. A further purpose of my invention is to automatically control the production of fuel mixture and limit it to a quantity sufficient only for immediate use.

Other objects of the invention will appear 25 as the description proceeds.

An embodiment of the invention is shown in the accompanying drawings in which the same reference numeral is applied to the same portion throughout, but I am aware 30 that there may be modifications thereof.

Fig. 1 is a side elevation of the complete machine with portions thereof broken away for purposes of illustration,

Fig. 2 is a plan view of the complete machine,

Fig. 3 is an end elevation of the machine, broken away to disclose certain features of the interior construction;

Fig. 4 is an end view of the working parts 40 of the machine on top of the evaporator pans looking in the opposite direction from Fig. 3,

Fig. 5 is a longitudinal sectional view of the gasolene measuring valve,

Fig. 6 is a transverse sectional view of the gasolene measuring valve,

Fig. 7 is a diagrammatic view illustrating the wiring for the operation of the motor for driving the machine, the tilting switches 50 being shown in their normally open position,

Fig. 8 is a plan view of the inlet pipes to the gasometers,

Fig. 9 is a plan view of the outlet pipes from the gasometers, and

Figure 10 is a vertical sectional view through the inlet and outlet valves of one of the gas holders.

The apparatus comprises a suitable longitudinal tank 1 installed upon a suitable base 2, and having two water compartments 3, 3' at one end for the gas holders. The rectangular tank 1 is closed at the top but not air tight and normally is filled with water in which are submerged a series of flat tubes 4, 4', in two series inclined from one end of the receptacle 1 toward the other end thereof, and back again, oppositely inclined, being connected at their ends by vertical portions 5.

In the present instance, there are eleven of the tubes 4, 4' oppositely inclined from top to bottom. These tubes have inlet pipes 6, 6' connected therewith and have the two outlet pipes 7, 7' connected with the lower trays. 70 The pipe 7, 7' connect with the pipes 8, 8', which latter is connected to a single pipe 9 leading to the pipes 10, 10' and in turn connected with the pipes 11 and 11' leading into the gas holders. See Fig. 8. The pipes 6, 6' are connected to two pipes 12, 12' which are in turn connected to a single valve 13 which receives its air from the receptacle 14 within which are suitable trays 15 carrying calcium chloride to remove the 80 water from the air drawn into the machine.

Mounted upon the top of the receptacle 1 are two plates 16 and 17 which form the support for the brackets 18 to 21 inclusive. These brackets support the gasolene tank 90 22. This gasolene tank has a switch block 23 mounted thereon carrying a knife switch 24. A lever 26 extends into the gasolene tank, and carries a float 25 and said float lever has a slotted link 27 pivotally connected therewith at one end. The slotted link serves to disconnect the switch 24 when the supply of gasolene runs low so as to prevent the machine from operating and drawing in air without the proper quantity of gasolene. 100

The plates 16 and 17 are connected together by means of two cross plates 29 and 30, which support a casing 31 containing the gasolene measuring valve 32. The gasolene measuring valve 32 has two depressions 105 as indicated at 33, 34, as in Fig. 6 and it

is formed on the end of a shaft 35 which projects through the casing 31.

A packing gland 36 prevents the escape of gasoline around said shaft. In order to hold the valve tightly against its seat, there is a pressure block 37 which has a tubular sleeve 38 within which is a spiral spring 39. A plate 40 bears upon this spring, and the screw 41 with the lock nut 42 passing through the detachable end piece 43 of the casing 31 determines the pressure to be brought upon the valve 32 holding it snugly against its seat to prevent the waste of gasoline and overloading of the trays.

15 A pipe 44 connects the gasoline valve with the gasoline tank, and a pipe 45 connects the gasoline valve with two pipes 46 and 47, which pipes are in turn connected to the trays 4, 4' respectively for the delivery of the gasoline thereto.

The shaft 35 has a spiral gear 47 thereon, and it is also journaled in a bearing in the cross member 48 also supported by the plates 16 and 17. The gear 47 is in mesh with a gear 50 on a shaft 51 journaled in bearings 52, 53 mounted on the top of one end of the plates 16, 17 respectively. The shaft 51 has two large gears 54, 55 thereon, which gears are each provided with 25 crank pins 56, 57 pivotally connected with the links 58, 59. The links 58, 59 are in turn pivotally connected with arms 60, 61 carried by shafts 62, 63 respectively. The shaft 62 is journalled to bearings 64, 65, 35 while the shaft 63 is journalled in two bearings 66, 67. These two shafts are aligned and carry arms 68, 69 and 70, 71 respectively for raising the gas holders 72, 73. The gas holders operate in the compartments 3, 3', which compartments are filled with water to the line indicated in Fig. 3 in order to provide a water seal for the gas.

The gas holders pass loosely over tubes 45 75, 76 between which and the outer walls of the compartments 3, 3', the water for the gas holders to work in is placed. The upper ends of tubes 75, 76 are closed by means of plates 77 each of which have two bosses 78, 79 with which the pipes 11 and 11' are connected. The plate at the top of the tube 76 is the same as the plate 77, and it has the pipes 11', 80' connected therewith. The pipes 80, 80' are the gas discharge pipes, and are connected by means of pipes 81, 81' to the gas discharge nozzle 82, said nozzle having a restricted opening to prevent the too rapid withdrawal of the gas without giving the machine time to operate.

60 The nozzle 82 is controlled by means of a valve 83. At the top of the inlet pipes 11, 11', the plate 77 has a bushing 84 screwed into said plate over the boss 78.

This bushing carries a valve 85 on a stem 65 86, which valve is held normally closed by means of the spiral spring 87, said spring bearing upon a plate 88 carried on the lower end of the valve stem. The valve 85 opens upwardly upon the raising of the gasometer. 70

In the boss 79, there is screwed the bushing 89. This bushing 89 has a depending pin 90 upon which is slidable the valve 91, and said valve is normally held closed by means of the spiral spring 92, said spring bearing upon a pin 93 at the lower end of the pin 90. This valve opens outwardly upon the descent of the gas holder. 75

In order to provide for the proper guidance of the gas holders as they are raised and lowered, there are guides 94 to 97 inclusive carried by the lower ends of the gas holders, and said guides bear on vertical guides 98 to 101 inclusive. In addition to the foregoing guides, there is a cross bar 85 102 over each compartment 3, 3', said cross bar having an opening at its center for vertical guides 103, 104 carried by the gasometers.

The arms 68 to 71 inclusive have cables 99 105 to 108 inclusive connected therewith and said cables are provided with weights 109, 110 at their lower ends. These cables also pass through guides 111, 112 on the sides of the gas holders near their tops, and said guides have large enough holes therethrough to permit the cables to move freely therein. The guides 111, 112 act as lugs to lift the gasometers when the weights are pulled up against them.

100 Each gas holder has a trip 113 thereon and each of the tubes 103, 104 has a stop as shown at 115. Each of said trips is to stop and start the motor respectively. This is accomplished by means of the mercury tube 105 switch 116 which is carried by a bell crank 117 pivotally mounted on a bracket 118 supported by the cross bars 102. There is one switch for each gasometer, and as shown in Fig. 1, the switch is in the open position 110 normally with the mercury at the lower end of the tube and out of contact with the contact terminal 119, although it is in contact with the terminal 120.

The inlet and outlet pipes have suitable valves at their lower ends as indicated at 121, 122 for cleaning purposes should that be necessary.

115 The machine is driven from the motor 123, from which a belt 124 extends to the pulley 125 on the shaft 126. This shaft is journaled in bearings 127, 128, and has a small gear 129 thereon in mesh with a larger gear 130 on the shaft 131. This latter shaft is journalled in two bearings 132 and 133 and has two small gears 134, 135 in mesh with the two large gears 54, 55 respectively. 120 125

In order to provide for the circulation of

the water around the evaporation trays and to prevent them from freezing up, there is the circulation pump 140. This pump is operated by the belt 141 from a pulley 142 on the shaft 131, and said pump takes its water through the pipe 143, and discharges it through the pipes 144 leading to the pipes 145, 146, and finally discharges it into the tank through the pipes 147, 148.

10 In Fig. 7, there is shown a diagrammatic view of the electrical connections for controlling the motor, in which the electrical feed wires are shown at 150, 151. Said wires lead to the contacts on the switch block 23, and from the knife switch 24 lead to the motor by way of the wire 152 and to the tilting switches 116 by the way of the wire 153. Wires 154, 155 connect the opposite terminals of the tilting switches with 20 the opposite pole of the motor.

The result of the foregoing construction is that whenever one of the gas holders goes down, that it will tilt its switch 116 in such a position as to start the motor; while, when 25 it rises, it will stop the motor as soon as its trip 113 tilts the switch contact, and in a similar way, the switch blades 124 will be disengaged when the gasoline in the tank 122 gets too low.

20 The operation of the apparatus is as follows: assuming the gas holder to both be charged with gas and in use, it will be seen that the gas holder 72 is free to fall and send its gas to the discharge pipes connected with the pipes 80 for distribution. As soon as it falls below the position illustrated in Fig. 3, its stop 115 will contact with its arm 117, and cause the motor to start. As soon as the motor starts, the gas holder will 40 begin to rise drawing air through the receptacle 14 into the gas holder, through the trays 4, 4' and the inwardly opening valve 85. At the same time, measured quantities of gasoline from the tank 22 will be delivered by the valve 32 to the tubes 4, 4', there being a fixed gear ratio between the shaft 51 and the shaft 35. At the same time, the pump will be circulating the water in the receptacle 1 around the evaporation 50 pans, and will thereby prevent them from freezing up. At the same time that the gas holder 72 is rising, the arms 70, 71 will be lowering the cables 107, 108 leaving the gas holder 73 suspended only by its charge of 55 gas.

It is, of course, assumed that the gas is being used under the pressure of the gas holder, and when the gas holder 73 has reached the bottom of its movement, the 60 previous operation will be repeated; but in the mean time, the gas holder 72 will have been raised to the limit of its movement, and as soon as its stop 113 contacts with its arm 117, it will cut off the current to the

motor, thereby stopping the motor after a 65 definite supply of the gasoline gas has been produced.

It will be apparent from the foregoing description, that the gas produced by the machine may be used as long as there is a supply of gasoline, or other liquid fuel, and that by the time one gas holder is emptied 70 that the supply of gas contained in the other will begin to be used while the just emptied gas holder will be inspirated and 75 freshly supplied.

While water has been spoken of as the medium for sealing the gas holders, it will be clear to those skilled in the art that oil, glycerine or any other suitable liquid may 80 be used for that purpose at will.

What I claim is as follows, but various modifications may be made in the construction shown in the drawing and above particularly described form, within the purview of my invention.

1. A carbureting machine, comprising a mixing chamber having an air inlet and a carburetted-air discharge outlet, means for introducing determinate quantities of gasoline into said chamber, a pair of vertically movable carbureted air induction and holding bells, water-sealed at their lower ends, the outlet from said chamber communicating through valved conduits with the interiors of said bells, means for automatically lifting said bells alternately, holding each bell in elevated position until the vacuum created therein is filled by carbureted air induced through the carburetor, and then permitting the filled bell to descend by gravity to thereby expel the contained carbureted air, and a common carbureted-air discharge outlet operatively connected to both said bells. 90 95 100 105

2. A carbureting machine, comprising a mixing chamber having an air inlet and a carburetted-air discharge outlet, means for introducing determinate quantities of gasoline into said chamber, a pair of vertically movable carbureted air induction and holding bells, water-sealed at their lower ends, the outlet from said chamber communicating through valved conduits with the interiors of said bells, elevating mechanism for lifting said bells alternately and holding each bell in elevated position to permit the vacuum created therein to be filled by carbureted air induced through said carburetor, and controlling means for causing said mechanism to release the elevated bell when the other bell has discharged its contents. 110 115 120

3. A carbureting machine, comprising a mixing chamber having an air inlet and an air discharge outlet, means for introducing determinate quantities of gasoline into said chamber, a pair of vertically movable gas induction and holding bells, water-sealed 125

at their lower ends, the outlet from said chamber communicating through valved conduits with the interiors of said bells, elevating mechanism for lifting said bells alternately and holding each bell in elevated position to permit the vacuum created therein to be filled by carbureted air induced

through said carbureter and means controlled by each of said bells when in lowermost position for causing the descent of the other of said bells.

In testimony whereof I have hereunto set my hand this 12th day of July, A. D. 1919.

ALFRED E. ROBERTS.
